PETROLEUM REFINING PROCESS

James Delcos, Hudson, Clyde M. Haas, Highland Heights, and Willas L. Vermilion, Jr., Lakewood, Ohio, assignors to The Standard Oil Company, Cleveland, Ohio, a corporation of Ohio

No Drawing. Filed Mar. 27, 1962, Ser. No. 182,945

1 Claim. (Cl. 208—134)

This invention relates to a method of upgrading a low quality petroleum distillate stream and to the resultant upgraded products. More specifically, the invention relates to alkylation of an intermediate distillate stream from a coking unit, and to the fractionated, alkylated products which include a gasoline fraction, a reformable fraction, a jet fuel fraction, a power assist fluid fraction and a fuel oil fraction.

In a conventional refinery operation, crude oil is first fractionated in a tower operating at atmospheric pressure, with the "bottoms" being subjected to further fractionation in a tower operating under vacuum conditions. The "bottoms" from the vacuum fractionator also known as "residual," constitute the feed to the coking unit.

For purposes of this disclosure, coking is defined as the process of cracking and/or distilling petroleum hydrocarbons to dryness. The products of the coking operation are divided into a gaseous overhead, one or more side streams and a coke residuum. The number and the boiling ranges of the side streams will vary with product demands and with the requirements of other refinery unit operations, which are fed with coker distillates. In one typical scheme the coker distillates are divided into a wet gas overhead, and in order of increasing boiling ranges, side streams comprising coker naphtha gasoline, coker intermediate distillate and coker gas oil. The stream with which this invention is concerned is the aforementioned coker intermediate distillate, a stream presently utilized as #2 or light furnace oil.

It is not possible to define with precision the composition or specifications of coker intermediate distillate because it is not a tailor-made petroleum product. It is, however, a well-known product to those skilled in the art and can be described as that coker distillate fraction boiling within the approximate range of 340-500° F. and having a composition containing approximately equal volume percentages ($\pm 5\%$) of paraffins, olefins, naphthenes, and aromatics. By way of example only, a coker intermediate distillate treated in accordance with the teachings of this invention had the following composition and specifications:

TABLE I

Hydrocarbon type	Vol. percent
Paraffins	27.4
Olefins	23.2
Naphthenes	23.3
Aromatics	26.1
Specific gravity	0.811
Boiling range, ° F.	350-450

According to the process of this invention, coker intermediate distillate is upgraded by reacting it with isobutane in the presence of an alkylation acid catalyst such as hydrofluoric acid or sulphuric acid. Any conventional alkylation process or apparatus may be used.

The following specific example describes the best mode contemplated for carrying out the process:

A York-Scheibel extraction column was used as the alkylation unit. A coker intermediate distillate feed having the characteristics described in Table I hereinabove was introduced at three points along the column; one inlet being located near the bottom of the column, a second mid-way up the column, and a third in the upper sec-

2

tion of the column. Isobutane was introduced along with the feed at the inlet located near the bottom of the column. Excess isobutane and product were withdrawn from the top of the column. Sulphuric acid was introduced at the upper portion of the column and withdrawn at the bottom of the column.

The product stream was treated to remove entrained acid and excess isobutane, and then fractionated.

The operating conditions of the process included the following:

TABLE II

Temperature, ° F.	48
Isobutane to olefin ratio, volume	14.3/1
Acid to olefin ratio, volume	3.6/1
Fresh acid strength, percent	99
Spent acid strength, percent	93

Fractionation of the product stream produced the fractions shown in the table below:

TABLE III

Fraction	Boiling Range, ° F.	Vol. Percent	Use
1	IBP-200	3	Gasoline.
2	200-400	75	Reformer feed.
3	400-500	14	Jet fuel.
4	500-550	6	Base stock for power assist fluid.
5	550+	2	Fuel oil.

Fractions 1 and 5 may be blended directly into gasoline and fuel oil, respectively; fractions 2 and 3 will generally require a light hydrogenation treatment to convert remaining olefins to paraffins, before these fractions can be used as reformer feed and jet fuel respectively. Fraction 4 boils higher than the starting feed and is a synthetic stock which can be blended with conventional power assist fluid additives such as viscosity index improvers, anti-oxidants, wear inhibitors and anti-rust materials.

It will be recognized that the operating conditions of the alkylation unit may be varied within reasonable limits from the specific conditions employed in the example described hereinabove. The following ranges may be used as a guide:

TABLE IV

Temperature, ° F.	40-120
Isobutane to olefin ratio, volume	10/1-30/1
Acid to olefin ratio, volume	1/1-5/1
Fresh acid strength, percent	95-99
Spent acid strength, percent	88-93

It is to be understood that other modifications of the present invention will suggest themselves to those skilled in the art upon reading the foregoing description.

It is intended that all such modifications be included as are defined in the appended claim.

We claim:

A method of upgrading coker intermediate distillate containing appreciable amounts of paraffins, olefins, naphthenes and aromatics, and boiling within the approximate range of 340° F. to 500° F. which comprises alkyinating isobutane with the olefins in the distillate in the presence of the other components in the distillate, employing a sulphuric acid catalyst, the alkyinating conditions including the following: (1) temperature within the range of 40° F. to 120° F.; (2) isobutane to olefin ratio within the range of 10/1 to 30/1 on a volume basis; (3) acid to olefin ratio within the range of 1/1 to 5/1 on a volume basis; (4) fresh acid strength within the range of 95% to 99%; (5) spent acid strength within the range of 88% to 93%; and fractionating the resultant product into a gasoline fraction boiling within the approximate range of

0° F. to 200° F., a reformer feed fraction boiling within the approximate range of 200° F. to 400° F., a jet fuel fraction boiling within the approximate range of 400° F. to 500° F., a power assist fluid base stock fraction boiling within the approximate range of 500° F. to 550° F. and a fuel oil fraction boiling at approximately 550° F. and above.
